US00D967630S

(12) **United States Design Patent** (10) **Patent No.:** **US D967,630 S**
(45) **Date of Patent:** **** Oct. 25, 2022**

(54) **CRATE**

(71) Applicant: **Georg Utz Holding AG**, Bremgarten (CH)

(72) Inventors: **Axel Ritzberger**, Altendorf (CH); **Peter Grishin**, Carmel, IN (US)

(73) Assignee: **Georg Utz Holding AG**, Bremgarten (CH)

(**) Term: **15 Years**

(21) Appl. No.: **29/835,266**

(22) Filed: **Apr. 18, 2022**

Related U.S. Application Data

(62) Division of application No. 35/510,536, filed on Sep. 18, 2020 (U.S. filing date under 35 U.S.C. 384), and having an international filing date of Sep. 18, 2020, now Pat. No. Des. 949,566.

(57) **CLAIM**

The ornamental design for a crate, as shown and described.

DESCRIPTION

FIG. 1 is a top perspective view of a first embodiment of a crate according to the present invention;

FIG. 2 is a bottom perspective view of the crate of FIG. 1;

FIG. 3 is a right side view of the crate of FIG. 1;

FIG. 4 is a left side view of the crate of FIG. 1;

FIG. 5 is a front view of the crate of FIG. 1;

FIG. 6 is a back view of the crate of FIG. 1;

FIG. 7 is a top view of the crate of FIG. 1;

FIG. 8 is a bottom view of the crate of FIG. 1;

FIG. 9 is a top perspective view of a second embodiment of a crate according to the present invention;

FIG. 10 is a bottom perspective view of the crate of FIG. 9;

FIG. 11 is a right side view of the crate of FIG. 9;

FIG. 12 is a left side view of the crate of FIG. 9;

FIG. 13 is a front view of the crate of FIG. 9;

FIG. 14 is a back view of the crate of FIG. 9;

FIG. 15 is a top view of the crate of FIG. 9; and,

FIG. 16 is a bottom view of the crate of FIG. 9.
